UNITED STATES PATENT OFFICE.

CHARLES J. KELLOWAY, OF WILMINGTON, NORTH CAROLINA.

RAILWAY-SWITCH MECHANISM.

Application filed January 22, 1923. Serial No. 614,202.

To all whom it may concern:

Be it known that I, CHARLES J. KELLOWAY, a citizen of the United States, residing at Wilmington, in the county of New Hanover and State of North Carolina, have invented certain new and useful Improvements in Railway-Switch Mechanism, of which the following is a specification.

My invention relates to railway switch mechanisms, and particularly to adjustable devices used in connection with such mechanisms for permitting relative motion between the switch and its operating means.

I will describe one form of mechanism embodying my invention, and will then point out the novel features thereof in claims.

In the accompanying drawings, Fig. 1 is a plan view showing one form of railway switch having associated therewith a device B embodying my invention. Fig. 2 is a view showing in front elevation, partly sectioned, the device B illustrated in Fig. 1. Fig. 3 is a sectional view on line III—III in Fig. 2.

Referring first to Fig. 1 the reference character A designates a railway switch comprising, as usual, two stock rails 4 and 4^a and two movable rails 2 and 2^a. The two movable rails 2 and 2^a are connected mechanically in the usual manner by a head rod 3. An operating rod 5 is attached to this head rod 3 by means of some suitable connection, as a lug 10. Rails 4 and 2 or rails 2^a and 4^a may thus be brought into engagement by moving operating rod 5 longitudinally in one direction or the other. As shown in the drawing, this motion is effected by means of a bell crank 6 connected with operating rod 5 and caused to swing about its pivot 11 by some actuating means such as a lever 9 through pipes 7 and 8 operably connected with this bell crank. Interposed between pipes 7 and 8 of the pipe line is a device B for adjusting the length of the stroke of operating rod 5.

Referring now to Figs. 2 and 3, the device B comprises a rod H connected with pipe 7 by some suitable means such as a screw sleeve K. A plunger G is connected with pipe 8 by a similar screw sleeve L. The rod H is provided with screw threads and is screwed into one end of a housing C. This housing is provided with a central recess C' and the distance by which rod H extends into this recess may be regulated

by screwing this rod in or out. A jam or lock nut D screws tight against housing C and retains rod H in any desired position with respect to this housing. A bushing F is screwed into the left hand end of housing C. The shank G' of plunger G passes freely through this bushing F but is provided with an upset end G² extending into recess C' which end is capable of engaging the inner end of bushing F. This bushing may be moved into or out of the housing C by screwing it in the proper direction, and a lock nut E is arranged to hold the bushing in any desired position by screwing tight against the end of the housing. Thus it is plain that motion of plunger G toward the left is limited by bushing F and toward the right by the end H' of rod H, and that during the movement of the plunger between these two extreme positions there is no motion of rod H and pipe 7. That is, the stroke of pipe 7 is now less than the stroke of pipe 8. By proper adjustments of bushing F and rod H in the housing C, the relative motions of the two parts of the pipe line, that is, the amount of lost motion between these parts may be accurately adjusted and so the stroke of the operating rod 5 may be accurately and conveniently regulated.

One important feature of a regulating device embodying my invention is that the operating parts are fully enclosed in the housing C, and so are completely protected from the weather and from damage due to water.

Although I have herein shown and described only one form of railway switch mechanism embodying my invention, it is understood that various changes and modifications may be made therein within the scope of the appended claims without departing from the spirit and scope of my invention.

Having thus described my invention, what I claim is:

1. A lost motion device for use in connection with a railway switch and its operating mechanism, said device comprising a cylindrical housing open at both ends, a rod entering said housing at one end and thereby closing such end and constituting an abutment within the housing, a hollow bushing entering the housing at the other end and constituting a second abutment within the housing, and a plunger slidably mounted in

said bushing and closing the associated end of the housing and movable between said two abutments.

2. In railway switch mechanism comprising switch rails, a head rod connecting said rails and an operating rod for moving the switch, the combination with the foregoing instrumentalities of a rod operably connected with said operating rod, a housing secured to said rod and provided with an internal chamber into which said rod projects, a bushing secured to said housing, a plunger passing freely through said bushing and having an upset end projecting into said chamber and capable of moving between two extreme positions wherein said upset end engages said bushing or said rod.

3. In railway switch mechanism comprising switch rails, a head rod connecting said rails and an operating rod for moving the switch, the combination with the foregoing instrumentalities of a rod operably connected with said operating rod, a housing, means for locking said rod in adjacent positions with respect to said housing, a bushing, means for locking said bushing in adjusted positions with respect to said housing, and a plunger for co-operating with said bushing or said rod.

4. In railway switch mechanism comprising switch rails, a head rod connecting said rails and an operating rod for moving the switch, the combination with the foregoing instrumentalities of a rod operably connected with said operating rod, a housing

screwed on said rod and having a chamber into which said rod extends, a bushing screwed into said housing and establishing an abutment within said chamber, a plunger passing freely through said bushing and provided with an upset end for co-operating with said rod or said abutment, and means for operating said plunger.

5. In combination, a railway switch, an operating rod for said switch, means for actuating said rod and comprising a plunger having an upset end adapted at times to engage said operating rod, and means surrounding the ends of said rod and said plunger for at other times engaging said upset end.

6. In combination, a railway switch, an operating rod for said switch, means for actuating said rod and comprising a plunger having an upset end adapted at times to engage said operating rod, and means attached to said rod and protecting the ends of said rod and said plunger for at other times engaging said upset end.

7. In combination, a railway switch, an operating rod for said switch, means for actuating said rod and comprising a plunger having an upset end adapted at times to engage said operating rod, and means attached to said rod for protecting the ends of said rod and said plunger, and means operably connected with said second means for at other times engaging said upset end.

In testimony whereof I affix my signature.

CHARLES J. KELLOWAY.
